TENTERING CLIP FOR GRIPPING MATERIAL OF VARYING THICKNESSES

Kenneth Elton Fish, Warwick, R.I., assignor to Bevis Industries, Inc., Providence, R.I., a corporation of Florida

Filed May 14, 1968, Ser. No. 729,092

Int. Cl. D06c 3/10

U.S. Cl. 26—62

4 Claims

ABSTRACT OF THE DISCLOSURE

This invention relates to tentering clips employing a controller, and particularly to an improved controller which is pivoted directly to the swinging gripping jaw, the controller being guided and provided with a face contour, counterweighted, so as to be drawn lightly into contact with the material by the movement of the swinging jaw, will pivot into position upon the material in a manner to insure gripping of the selvedge edge by the jaw regardless of the thickness of the material, to thereby accommodate materials of varying thicknesses.

It is another object of the present invention to provide a controller for a tentering clip jaw which is more sensitive, in relation to the selvedge edge of the material to be clamped to the clamping position of the clamping edge of the jaw.

It is a further object of the present invention to provide a controller for a tentering clip jaw which will allow the clamping edge of the jaw to clamp thin material near the front edge of the clamping plate and to clamp thick material near the back edge of the clamping plate with a proper clamping force.

Other objects of the present invention will be pointed out in part and become apparent in part in the following specification and claims.

Referring to the drawings in which similar characters of reference indicate corresponding parts:

FIG. 1 is a perspective view of a tentering clip provided with the new and improved controller.

FIG. 2 is a horizontal cross-sectional view taken along line 2—2 of FIG. 1.

FIG. 3 is a vertical cross-sectional view taken along line 3—3 of FIG. 2.

FIG. 4 is a vertical cross-sectional view taken along line 4—4 of FIG. 2.

FIG. 5 is a perspective view of the controller, per se.

FIG. 6 is a front elevational view of FIG. 1.

FIG. 7 is a plan view of FIG. 1.

FIG. 8 is a fragmentary cross-sectional view through the tentering clip, similar to FIG. 3, showing the jaw and controller in material receiving position.

FIG. 9 is a perspective view of another form of tentering clip illustrating a modified form of controller construction.

FIG. 10 is a fragmentary perspective view, partly in section, illustrating the construction of the controller shown in FIG. 9.

FIG. 11 is a perspective view of the modified form of controller construction.

Referring to the drawings, the tentering clip consists of body having a horizontally disposed base 11 terminating in a front ledge 12 provided with an opening or slot 13, a tail section 14, a dependent central section 15 extending sidewise in opposite directions to provide a first upper ear 16 spaced apart and parallel to a first lower ear 17 and an opposite second upper ear 18 spaced apart from a second lower ear 19. Said ears 18 and 19 are parallel, respectively, to said first upper ear 16 and

2

first lower ear 17. Two spaced apart arms 20, 21 project upwardly from said base 11 to extend in a forwardly direction to overlie said horizontally disposed base 11 and said front ledge 12. A bridge 22 unites arms 20, 21 together to provide rigidity to said arms 20, 21. Pivots mounted between spaced apart arms 20, 21 upon a pintle 23 supported on opposite ends in arms 20, 21, is a jaw 24 provided with a projection 25 and a clamping edge 26. Jaw 24 is loosely hinged to pintle 23 between spaced apart arms 20, 21, so as to be normally free to move automatically into vertical relation under the action of gravity into clamping position with a horizontally disposed clamping plate 27 fastened to ledge 12. Clamping plate 27 is provided with a slot 28 which overlies opening 13.

The foregoing is a description of a tentering clip well known to the art, but modified in the following manner to accommodate the new and improved controller to be hereinafter described.

20 A bifurcated bracket 30 having spaced apart fingers 31, 32 is fastened to or integrally connected to said body and spaced apart arms 20, 21. A pin 33 is supported in spaced apart fingers 31, 32. Two spaced apart legs 34, 35 are fastened to or integrally connected to jaw 24 and a shaft 36 is supported in legs 34, 35.

25 A controller, generally indicated at 38, consists of a body member 42 having a forked extension comprising an upper prong 48 and a lower prong 47. Said body member 42 is also provided with a bearing 41 and a material engaging face 39 provided with a thin material engaging area 43 and a thick material engaging area 44.

30 Said bearing geometrically divides said body member 42 into two sections. One section being the forked extension and material on one side of the vertical plane passing through the axis of the bearing 41. The second section being the material on the opposite side of said vertical plane and which is provided with the material engaging face 39. It has been found desirable to have both sections of body members 42 of approximately equal weight. To that end, upper prong 48 is of an increased mass of material to form a counterweight to the second section.

35 The contour of the material engaging face may be cam generated to accommodate material varying in thickness from extremely thin micro-inch plastic film at point 45 to carpet thickness at point 46. Empirically, it has been found that material engaging face 39 may be arcuate and in fact be an arc of a circle, struck from the center of bearing 41.

40 Controller 38 is hinged to shaft 36 through bearing 41 and is slidably suspended to pin 33 by means of prongs 48, 47 of the forked extension.

45 In operation, a cam (not shown) will engage projection 25 to pivot jaw 24 around pintle 23 into open position.

50 FIG. 8 is similar to FIG. 3 and illustrates the position of the jaw 24 and controller 38 when the jaw 24 is in open or material receiving position; clamping edge 26 is away from clamping plate 27. The jaw and controller are about to initiate movement into jaw closing or material clamping position, which is the position shown in FIG. 3.

55 As will be seen from a comparison of FIG. 8 with FIG. 3, the controller 38 is hinged to jaw 24 by means of shaft 36 and is slidably mounted to pin 33 through prongs 48, 47 which form an elongated slot therebetween. As the jaw pivots from open to closed position, the controller 38 falls in two directions, namely, on the arc having a center on the axis of the pintle 23, and below the arc having a center on the axis of shaft 36. The body 42 of the controller rotates in a clockwise direction as the shaft 36 swings in

an arc around pindle 23 in a counterclockwise direction, as viewed in FIGS. 3 and 8. The suspension of controller 38 about pin 33 and shaft 36, with the face 39 counterweighted at prong 48, allows face 39 to engage the material with a very light touch so that face 39 does not force the cloth into slot 28. Face 39 rides the cloth as the cloth is pulled in the direction of arrow A in FIG. 8. Point 46 of the body 42 approaches to engage the material first. As jaw 24 swings in a counter-clockwise direction, shaft 36 moves toward clamping plate 27. Upper prong 48 riding upon pin 33 suspends the counterweight between pin 33 and shaft 36 and rotates arcuate body portion 42 in a clockwise direction with thick material engaging surface 44 first moving toward clamping plate 27 to engage the material. If the material is not engaged the controller 38 continues to rotate until the thin material engaging surface 43 rotates far enough and the jaw 24 simultaneously swings far enough for surface 43 to engage and ride the material. The material always covers slot 28 and moves toward front edge 12. As soon as the material moves past slot 28, arcuate body portion 39 drops into slot 28 thereby initiating the clamping of the cloth between clamping edge 26 and clamping plate 27 by releasing jaw 24 to the action of gravity.

Reference is now made to FIGS. 9 and 10, wherein, a tentering clip is shown in a modified form to the tentering clip illustrated in FIGS. 1 thru 8; and is adapted to function with the controller, so as to grip material of varying thicknesses.

The tentering clip, in modified form, consists of a body having a horizontally disposed base 11A terminating in a front ledge 12A provided with an opening or slot 13A, a dependent central section extending sidewise in opposite directions to provide a first upper ear 16A spaced apart and parallel to a first lower ear 17A and an opposite second upper ear 18A spaced apart from a second lower ear (not shown) but equivalent to ear 19 shown in FIG. 6.

Two spaced apart arms 20A, 21A project upwardly from said base 11A to extend forwardly where arms 20A, 21A merge into a bracket 9 which overlies said horizontally disposed base 11A and said front ledge 12A. Pivotally mounted upon a pindle 23A supported in bracket 9 is a jaw 24A provided with a projection 25A and a clamping edge 26A. Jaw 24A is loosely hinged to pindle 23A, so as to be normally free to move automatically into vertical relation under the action of gravity into clamping position with a horizontally disposed clamping plate 27A fastened to ledge 12A. Clamping plate 27A is provided with a slot 28A vertically aligned with slot 13A.

A bracket 30A is fastened to or integrally connected to base 11A so as to constitute part of the body structure of the tentering clip. A pin 33A is supported in bracket 30A and projects sidewise therefrom. A leg 34A is fastened to or integrally connected to jaw 24A.

A controller, generally indicated at 38A, consists of a body member 42A having a forked extension comprising an upper prong 48A and a lower prong 47A. Said body member 42A is also provided with a bearing 41A and a material engaging face 39A provided with a thin material engaging area 43A and a thick material engaging area 44A.

Upper prong 48A, lower prong 47A and body member 42A may be bifurcated as shown in FIGS. 10 and 11.

Said bearing 41A geometrically divides said body member 42A into two sections. One section being the bifurcated extension prongs 47A, 48A and the mass of material on one side of a vertical plane passing through the axis of the bearing 41A. The other section constitutes the mass of material on the opposite side of said vertical plane and which is provided with the material engaging face 39A and area 43A. It has been found desirable to balance section one against section two around bearing 41A. Therefore, section one should be equal in weight to section two. To that end, upper prong 48A is of an increased mass of material to form a counterweight to section two.

The contour of material engaging face 39A, bifurcated, is the same as stated for face 39, thereby, to accommodate material of varying thicknesses.

Controller 38A is hinged to a shaft 36A through bearing 41A fastened in leg 34A. Controller 38A is slidably suspended to pin 33A by means of bifurcated prongs 48A and 47A of the forked extension.

Controller 38A operates in the identical manner described for the operation of controller 38.

Having shown and described preferred embodiments of the present invention by way of example, it should be realized that structural changes could be made and other examples given without departing from either the spirit or scope of this invention.

What I claim is:

1. In a tenter clip for gripping materials of varying thicknesses comprising a horizontally disposed base having a clamping surface provided with a slot, a vertically upstanding bracket having a pair of spaced apart arms which project sidewise from said bracket to overlie said clamping surface, a pindle mounted in said pair of arms, a jaw having a projection and a clamping edge, said jaw loosely hinged to said pindle to be normally free to move automatically into clamping engagement with said clamping surface, that improvement in tenter clip jaws comprising a bracket attached to said base, a leg attached to and extending from said jaw toward said bracket, a shaft supported in said leg, a pin supported in said bracket, a controller comprising a body member having a forked extension, consisting of an upper prong, and a lower prong, said forked extension being counterweighted, and a cloth engaging face, having a thin material engaging area and a thick material engaging area, said body member also having a bearing, said bearing pivotally mounted to said shaft to hinge said controller to said jaw, said forked extension slidably engaging said pin to slidably suspend said controller to said base, whereby movement of said jaw from open to closed position pulls said body member toward said jaw, and pivots said face from said thick material engaging area to the thin material engaging area as said face moves into material engaging position, said counterweighted forked extension offsetting the pressure of said face upon the material.

2. A tenter clip for gripping material of varying thicknesses as defined in claim 1 wherein said cloth engaging face is an arcuate surface concentric to said shaft.

3. A tentering clip including: a body having a horizontally disposed base terminating in a front ledge, an opening, a tail section, a dependent central section extending sidewise in opposite directions to provide a first upper ear, a first lower ear spaced apart and parallel to said first upper ear, a second upper ear parallel and opposite to said first upper ear, a second lower ear spaced apart and parallel to said second upper ear, two spaced apart arms projecting upwardly from said base and extended to overlie said horizontally disposed base and said front ledge, a clamping plate having a slot fastened to said front ledge, said slot aligned with said opening, a pindle supported in said two spaced apart arms, a jaw provided with a projection and a clamping edge, said jaw pivotally mounted on said pindle so as to be normally free to move into clamping position with said clamping plate, a bifurcated bracket having spaced apart fingers fastened to said body, a pin supported in said spaced apart fingers, two spaced apart legs fastened to said jaw, a shaft supported in said two spaced apart legs and a controller consisting of a hub having a bearing supported upon said shaft and between said spaced apart legs, an arcuate body portion having a pivotal center in the center axis of said hub, a thin material engaging surface on said arcuate body portion, a thick material engaging surface on said arcuate body portion contiguous to said thin material engaging surface, a forked extension having a lower prong extending from said arcuate body portion, an upper prong extending from said arcuate body portion and

forming an elongated space with said lower prong, said upper prong being tapered to provide a counterweight to said arcuate body portion, said lower prong and said upper prong engaging said pin with said pin located in said elongated space, whereby pivotal movement of said jaw toward closed position presents said thick material engaging surface in register with said clamping plate and slot, the dropping of said arcuate body portion into said slot simultaneously causing said clamping edge to assume jaw closed and clamping position.

4. In a tentering clip including a body having an arm, a clamping plate provided with a slot, and a jaw having a clamping edge pivotally mounted to said arm with said clamping edge engageable and disengageable with said clamping plate, that improvement comprising a bifurcated bracket attached to said body, a leg attached to and projecting from said jaw, a shaft supported in said leg, a pin supported in said bracket, a controller comprising a hub, means pivotally mounting said hub to said shaft, an arcuate body portion having a pivotal center in the axis of said shaft, a thin material engaging surface on said arcuate body portion, an outwardly bulging arcuate thick material engaging surface on said body portion contiguous to said thin material engaging surface, a forked extension having a lower prong extending from said arcuate body portion, an upper prong extending from said arcuate body portion and forming an elongated space with said lower prong, said upper prong being

counterweighted, said upper prong slidably engaging said pin, whereby pivotal movement of said jaw toward closed position pivots said body portion around said shaft to present said thick material engaging surface in register with said slot and further pivotal movement of said jaw toward closed position pivots said body portion around said shaft to present said thin material engaging surface in register with said slot, the dropping of said body portion into said slot simultaneously placing said clamping edge in clamping relation with said clamping plate.
